LABEL APPLYING MACHINE

George W. von Hofe, Bound Brook, N. J., assignor
to New Jersey Machine Corporation, Hoboken,
N. J., a corporation of New Jersey

Application August 2, 1938, Serial No. 222,605

22 Claims. (Cl. 216—55)

The invention relates to label applying machines and has for its object to provide a novel and simple machine for applying labels having coatings which become adhesive in the presence of heat. The invention contemplates primarily the provision of a novel machine whereby labels having thermo-plastic coatings may be efficiently applied to the articles for which said labels are intended. Other more specific objects will appear from the description hereinafter and the features of novelty will be pointed out in the claims.

In the accompanying drawings, which illustrate examples of the invention without defining its limits, Fig. 1 is a side elevation of the novel machine in one form with parts in section; Fig. 2 is a fragmentary sectional elevation of a label hopper and associated parts included in the machine; Fig. 3 is a side elevation partly in section of another form of the novel machine; Fig. 4 is a detail section of one form of label pick-up device; Fig. 5 is a similar view of another form of pick-up device, and Fig. 6 is a detail section of a label and its coating on an enlarged scale.

For the purpose of simplification, the term "label" is used throughout the description, it being understood that this term is intended to include any equivalent elements such as for instance decalcomanias and the like, and said term accordingly is to be so construed.

The novel labeling machine, in the form illustrated in Fig. 1, consists of a frame 10 of suitable type and dimensions on which an upright hopper 11 is supported in any suitable manner at what may be termed the pick-up station of the machine. The hopper 11 is designed to contain a supply of labels 12 arranged therein in the form of an upright stack resting upon the bottom 13 of said hopper 11 as shown in Fig. 1; conventional elevating means 14 is included in the machine for raising the bottom at periodic intervals to thereby restore the top of the stack of labels 12 to a predetermined height or in other words to maintain the top of said stack of labels 12 at a substantially constant feeding level.

The instant machine is designed primarily to operate with labels 12 which, previous to their insertion into the hopper 11, have been coated with adhesive on one face, and more particularly with labels 12 having a thermo-plastic coating *a* which becomes adhesive in the presence of heat; the labels 12 generally are stacked in the hopper 11 with the coated surfaces, and more especially the thermo-plastic coatings *a*, facing downward in the stack.

The previously mentioned elevating means 14 may be automatically controlled in any well-known way to periodically raise the bottom 13 of the hopper 11 to thereby restore the top of the stack of labels 12 to a predetermined feeding level. In the illustrated example, the automatic control is exemplified by a feeler 15 vertically slidably in an upright guide 16 and connected by means of a link 17 with a bell crank lever 18 pivoted at 19 upon the frame 10 of the machine; the lever 18 carries a roller 20 arranged to be acted upon by a cam 21 to vertically reciprocate the feeler 15 in operative synchronism with the means whereby individual labels 12 are successively removed from the upper end of the stack at the aforesaid pick-up station as will be more fully set forth hereinafter. The cam 21 is fixed upon a rock-shaft 22 suitably journaled on the frame 10 and operated in predetermined operative timing with the associated elements of the machine by any conventional mechanism, exemplified by the rack 22^a in mesh with a segment 22^b fixed on the shaft 22.

For the reason to be more fully pointed out hereinafter, the machine includes a blowing means which is designed to develop definite air separation between successive terminal and adjacent labels 12 at the upper end of the stack in the hopper 11 to thereby insulate said labels 12 from each other during the operation of removing successive terminal labels 12 from said stack. In the illustrated example the hopper 11 is accordingly provided at least at one side near its upper end with a plurality of air vents 23 directed toward the interior of the hopper 11 and communicating externally thereof with an air nozzle 24 suitably fixed in place as shown for instance in Fig. 1; the nozzle 24 may be connected by means of a tube 25 with a source of air under pressure controlled in a manner to effect the desired results. In addition, provision is preferably made to prevent the air separated labels 12 at the top of the stack from being blown out of the hopper 11 by the action of the developed air separation, without interference with the removal of successive terminal labels 12 from the upper end of said stack. As shown in Fig. 2 the hopper 11 may accordingly be provided with retaining pins 26 and 27 projecting inwardly over the upper end of the stack of labels 12; in the preferred arrangement the pins 27 may be adjustable laterally of the hopper 11 and may comprise parts of screws 28 adjustably mounted on said hopper 11 and held against unintentional movement by means of springs 29.

The articles A to which the labels 12 are to be applied may be supported in label receiving position at a label applying station in the machine, in any convenient way, as by means of a support 30 carried by an upright standard 31 as shown in Fig. 1.

In the operation of the novel machine under discussion, successive terminal labels 12 are removed by transferring means in individual succession from the top of the stack in the hopper 11 and are coincidentally heated to render the coating a or its equivalent adhesive; subsequent to the removal from the stack and while the application of heat thereto is continued, each label 12 is conveyed to the applying station and applied by said transferring means to the article A located at said station at the time. The transferring means in the form shown in the illustrated example consists of a carriage 32 slidably mounted on a horizontal guide rail 33 conveniently supported on the frame 10 of the machine, suitable stops 34 and 35 preferably being provided to arrest the reciprocation of said carriage 32 in opposite directions. The means whereby the carriage 32 is actuated lengthwise of the rail 33 is exemplified by an arm 36 fixed upon the rock-shaft 22 and having its free end pivotally connected with a coupling rod 37 which in turn may be yieldingly and pivotally connected at 38 with a lug 39 forming part of or fixed upon the carriage 32 as illustrated in Fig. 1.

The transferring means further includes a pick-up device for removing terminal labels 12 from the top of the stack in the hopper 11 in individual succession. In the illustrated example, the pick-up device is of the preferred suction operated type and comprises a head 40 connected with a convenient source of suction for instance by means of a flexible tube 41 constructed and arranged to permit the various operative steps to be performed without interference; suitable provision is made in any well-known way to control the suction developed in the head 40 in properly timed synchronism with the steps of picking up, transferring and applying the labels in an operative cycle of the machine. The head 40 is associated with a heating unit 42 of any suitable character and preferably of conventional electrical type located in an electrical circuit exemplified by the wires 43.

The illustrated pick-up device further consists of a pick-up plate 44 which preferably is removably carried by the head 40 for instance as illustrated in Figs. 4 and 5. In the form shown in Fig. 4 the plate 44 includes a depending section 45 provided upon its lower surface with a resilient pad 46 consisting of porous, heat conducting material fixed in place in any convenient manner; the material of which the pad 46 is constructed may for instance comprise a mass of fine wires of the type commonly referred to as steel wool or copper wool. Such materials are excellent conductors of heat and provide a pad 46 of sufficient resiliency to conform its active surface to the surface of the articles A during the application of the labels 12 thereto; the materials in question are however deficient in the development of a vacuum at a given point or in other words of rendering the suction in the head 40 effective at the active surface of a given pad 46. To overcome this condition a plurality of preferably resilient tubes 47 are provided which are embedded in the pad 46 and terminate at the active surface thereof and extend through

the section 45 and plate 44 into communication with the interior of the suction head 40.

Instead of being constructed as shown in Fig. 4, a pick-up device of the type illustrated in Fig. 5 may be substituted, which device includes a pick-up plate 44^a and a depending section 45^a the lower portion of which constitutes a flexible pad 46^a of non-porous material such as heat resistant rubber. The pad 46^a is provided with apertures 47^a extending through the same and terminating at the active surface of said pad 46^a as shown; the apertures 47^a are located in communicating registry with corresponding apertures 47^b extending through the section 45^a and plate 44^a into communication with the interior of the suction head 40 on which said plate 44^a may be removably mounted in the same way as shown in Fig. 4.

In either case the pick-up device, as shown in the drawings, may be carried by a member 48 which is mounted on the carriage 32 so as to be vertically slidable thereon. Any conventional mechanism may be provided for reciprocating the member 48 on the carriage 32 at the proper stages in the operative cycle of the machine. For instance, as illustrated in Fig. 1, the member 48 may carry a roller 49 adapted to travel along a horizontally extending track 50 arranged to be raised and lowered in any well-known way to reciprocate the member 48 and its associated elements relatively to the carriage 32 as will appear more fully hereinafter. A spring 51 may be attached at one end to the rail 33 and at its other end to a lug 52 on the member 48 for the purpose of assisting the downward movements of the latter and its associated elements; this spring 51 in some instances may be omitted and gravity alone relied upon to move said member 48 downwardly as the track 50 is lowered.

In describing the operation of the novel machine in the form so far described it will be assumed that in Fig. 1 the pick-up device exemplified by the suction head 40 is about to start a return movement to the pick-up station at 45 which the stack of labels 12 is located.

The rock-shaft 22 is operated in one direction in a manner to swing the arm 36 to the right in Fig. 1 to develop a pull upon the coupling rod 37 whereby the carriage 32 is propelled along the rail 33 in the same direction until the stop 35 is engaged by said carriage 32. At this stage the suction head 40 or equivalent pick-up device is located at the pick-up station in vertical registry with the stack of labels 12 thereto. In the meantime the cam 21 by acting upon the bell-crank lever 18 has raised the feeler 15 to an inoperative position in which it does not interfere with the operation of the suction head 40 in the intended manner.

At the proper point in the operative cycle of the machine, the track 50 is lowered to correspondingly lower the member 48 on the carriage 32 and to thereby bring the active face of the suction head 40 above and in registry with the hopper 11 in spaced relation to and within suction range of the upper end of the stack of labels 12 for instance as shown in Fig. 2. During at least this phase in the operation of the novel machine, and in some instances during a complete operative cycle thereof, air pressure is effective in the air nozzle 24 to develop jets of air through the air vents 23 directed inwardly into the hopper 11 and transversely across the same to develop confined air cushions therein on which the upper terminal label 12 in the supply stack

and preferably one or more contiguous labels 12 in said stack are floated in separated relation to each other in the hopper 11 at the upper end thereof; in other words, the upper terminal label 12 and preferably one or more labels 12 contiguous thereto are definitely separated from each other by the aforesaid confined air cushions developed by the jets of air as illustrated in Fig. 2. The terminal label and adjacent labels 12 are prevented from being blown out of said hopper 12 by the retaining pins 26 and 27. It will be noted, when the suction head 40 or equivalent pick-up device is in the pick-up position relatively to the stack of labels 12, that the active face of said suction head 40 or its equivalent is located in spaced relation to but within suction range of the upper terminal label 12. The latter accordingly is drawn from the hopper 11 by the suction developed in the suction head 40 in properly timed relation to effect this result, into contact with the active face of said suction head 40 so that said terminal label 12 is deposited and held upon said active face of said suction head 40 in the conventional manner.

Because of this withdrawing of said terminal label 12 by the action of the suction head 40, and due to the heat insulation provided by the layers of air which separate said terminal label 12 from adjacent labels 12 and several of the latter from each other, the heat from the heated suction head 40 is prevented from penetrating into the stack. As a result of this arrangement, the thermoplastic coating *a* of the actual terminal label 12 which is being removed from the supply stack at the time and which is softened and rendered adhesive by the heated suction head 40 is prevented from adhering to the next adjacent label 12 in said stack; at the same time the thermoplastic coatings *a* of the next succeeding labels 12 in said stack are also protected against softening by the heat of said suction head 40 and consequently no undesirable adhesion between adjacent labels 12 in said stack is developed as will be apparent.

When the terminal label 12 has been drawn from the supply stack and deposited and held upon the active surface of the suction head 40 or equivalent pick-up device, the track 50 is raised to correspondingly elevate the suction head 40 or its equivalent with said label 12 thereon. With the track 50 remaining in its elevated position the rock-shaft 22 is actuated in a reverse direction to swing the arm 36 to the left in Fig. 1 and to thereby correspondingly move the carriage 32 in the same direction along the rail 33. As these operations take place, the roller 49 travels along the elevated track 50 and thereby maintains the suction head 40 with the label 12 thereon in a raised position without interfering with the movement of the carriage 32 along the rail 33, and the parts finally reach the position shown in Fig. 1 in which the suction head 40 is located at the label applying station. Throughout the travel of the carriage 32 and the suction head 40 from the pick-up station to the label applying station, the label 12 carried by the suction head 40 at the time has been heated by the heat of the heating element 42 and the thermo-plastic coating *a* of said label 12 has been softened and rendered inherently adhesive.

When the label applying station has been reached, the track 50 is lowered and the member 48 moves downwardly on the carriage 32 to thereby cause the suction head 40 to deposit the label 12 carried thereby upon the article A which has previously been placed upon the support 30 in 75

label receiving position. As the pad 46 of the suction head 40 is resilient, the active face thereof, for instance under the influence of the spring 51, will conform itself to the surface contour of the article A with the result that the label 12 will be uniformly and efficiently applied to said article A to which it is adhesively attached by the thermo-plastic coating *a*. It will be noted that the label 12 is subjected to the heating influence of the heated suction head 40 or its equivalent until the application of said label 12 to the article A has been completed. The thermo-plastic coating *a* of said label 12 is thereby maintained in a softened condition of maximum adhesiveness until said label has been efficiently applied to the given article A.

When the application of the particular label 12 to the particular article A has been completed, the suction in the suction head 40 is discontinued and the latter is lifted on the carriage 32 by the action of the track 50 on the roller 49 and member 48. The labeled article A is then removed from the support 30 or otherwise disposed of and the operations set forth above are repeated.

25 In the form illustrated in Fig. 3 the novel machine may be of the same general construction and operate in the same general manner as the machine illustrated in Fig. 1 and described hereinbefore.

30 In the machine of Fig. 3 the pick-up device is also exemplified by a suction head 40^a similar to the suction head 40, but differing therefrom in that the suction head 40^a is not provided with a heating device; this is not an arbitrarily necessary difference as in some instances it may be desirable to provide the suction head 40^a with means for imparting heat thereto corresponding for instance to the heating unit 42 of the suction head 40.

40 In addition to elements similar to those included in the form of machine first described, the machine under discussion is provided with means for developing pressure upon the labels in the presence of heat subsequently to the initial deposit of said labels upon the articles for which they are intended.

45 The pressure developing means, in the form illustrated in Fig. 3, consists of a pressure member 53 carrying a pressure pad 54 of suitable type and preferably having an inherent resiliency sufficient to enable said pressure pad 54 to conform to the surface contour of the article A when operating the pressure member 53 to apply a label 12 thereto. Suitable provision is made for heating the pressure pad 54 as by associating therewith, in any convenient manner, a heating device for instance of the type exemplified by the electrical heating unit 42 of Fig. 1 and likewise located in an electric circuit which includes the wires 55.

50 As shown in Fig. 3, the pressure member 53 is carried by a plunger 56 vertically slidable in a guideway 57 suitably supported in proper position upon the frame 10 of the machine. The plunger 56 is vertically reciprocated in the guideway 57 to correspondingly operate the pressure member 53 and its pressure pad 54 in properly timed relation with the other elements of the machine in any convenient manner, as by means of a lever 58 having its free end loosely connected with the upper end of said plunger 56 as indicated in Fig. 3. The lever 58 may be loosely mounted on the shaft 22 for independent pivotal movement thereon by suitable mechanism

exemplified by the link 59 pivotally connected at 60 with a bracket 61 carried by said lever 58. The construction and arrangement is such that the pressure member 53 in its raised inoperative position will not interfere with the positioning of the suction head 40^a or its equivalent at the label applying station or its operation thereat.

During an operative period of the machine shown in Fig. 3, the carriage 32 is reciprocated on the rail 33 and the suction head 40^a is operated relatively thereto to pick up successive terminal labels 12 from the upper end of the supply stack at the pick-up station and to convey said labels to the label applying station. At the latter station the suction head 40^a is operated downwardly at the proper time to initially deposit the label 12 carried at the time upon the article A which in the meantime has been placed in label receiving position on the support 30. When this initial deposit of said label 12 has been effected, the suction in the suction head 40^a is discontinued and the latter is raised on the carriage 32; it will be understood that the thermo-plastic coating *a* of the particular label 12 is sufficiently adhesive to cause the initially deposited label to adhere to the article A as the suction head 40^a moves upwardly on the carriage 32. The latter is then shifted to the right on the rail 33 to return the suction head 40^a to the pick-up station for operation thereat in proper timing to remove the next successive terminal label 12 from the supply stack.

As the suction head 40^a with the carriage 32 is thus moved to the right, the lever 58 will be actuated to shift the plunger 56 downwardly in the guideway 57 and to thereby shift the pressure pad 54 of the pressure member 53 into contact with the previously deposited label 12 on the article A. The said label 12 is thereby subjected to the action of the heated pad 54 and the thermo-plastic coating *a* thereof is accordingly softened and rendered highly adhesive; at the same time the pressure member 53 will develop a pressure whereby the pressure pad 54 is caused to conform to the surface contour of the article A and the label 12 is evenly and adhesively applied thereto. The lever 58 is then actuated to raise the plunger 56 in the guideway 57 and to correspondingly lift the pressure pad 54 and pressure member 53 away from the labeled article which is removed from the support 30 or otherwise disposed of. The described cycle of operations is then repeated and continued throughout a given operative period of the machine.

In the form of the machine first described, successive terminal labels 12 are removed from the supply stack by a pick-up device which transfers said labels to the applying station and heats said labels during such transfer to render the thermo-plastic coatings *a* highly adhesive, and then applies said labels 12 to the articles A at the label applying station; the heating of the labels 12 continues throughout the application thereof to the articles A so that efficient adherence is developed between said article A and the given label 12.

In the machine of Fig. 3 successive terminal labels 12 are likewise removed from the supply stack by a pick-up device and transferred thereby to the label applying station. At the latter the pick-up device is operated to initially deposit successive labels 12 upon successive articles A, said initially deposited labels 12 being subsequently firmly pressed into adhesive connection with

said articles A by the heated pressure pad of a pressure member.

In both instances, the adhesive application of the labels is effected in the presence of heat by means of a pad sufficiently resilient to conform to the surface contour of the articles A, and to thereby evenly and adhesively apply the labels 12 thereto. The pad in each instance is operatively controlled by mechanism which develops a label applying movement at the label applying station; in the selected examples of the novel machine each pad is carried by a member which is reciprocated at the label applying station to develop said label applying movement.

The form of the novel machine illustrated in Fig. 1 is of the utmost simplicity in that the removal of successive terminal labels from the supply stack, the transfer thereof to the label applying station, and the adhesive application of said labels to successive articles thereat, is controlled by the same member and the mechanism of which it is a part.

In all of its forms the novel machine is particularly adapted for handling labels or their equivalent provided with thermo-plastic coatings which become adhesive in the presence of heat; it will be understood however that the machines may be utilized in connection with any type of adhesively coated labels or their equivalent, which by the use of heated appliances may be applied to associated articles with greater efficiency than is otherwise possible.

Various changes in the specific forms shown and described may be made within the scope of the claims without departing from the spirit of the invention.

I claim:

1. In a machine of the kind described, the combination of a support located at an applying station for supporting articles thereat in label receiving position, a hopper located at a pick-up station spaced from said applying station for confining a stack of labels having thermo-plastic coatings, a carriage reciprocable between said stations, a suction head movably mounted on said carriage and provided with a resilient heated pad on its active face, said suction head being movable relatively to said carriage at the pick-up station for removing successive terminal labels from said hopper and at said applying station for applying said labels to successive articles thereat, said heated resilient pad heating the thermo-plastic coatings in transit between said stations and during application thereof to said articles and conforming itself to the surface contour of the latter, and an air nozzle communicating with and supplying air to the interior of said hopper, the latter confining the introduced air in the form of insulating air cushions whereby penetration of heat from the heated resilient pad into said hopper is prevented.

2. In a machine of the kind described, the combination of a support located at an applying station for supporting articles thereat in label receiving position, a hopper located at a pick-up station spaced from said applying station for confining a stack of labels having thermo-plastic coatings, a carriage reciprocable between said stations, a suction head movably mounted on said carriage and provided with a resilient heated pad on its active face, said suction head being movable relatively to said carriage at the pick-up station for removing successive terminal labels from said hopper and at said applying station for applying said labels to successive articles thereat,

said heated resilient pad heating the thermo-plastic coatings in transit between said stations and during application thereof to said articles and conforming itself to the surface contour of the latter, and means for developing insulating air cushions therein whereby penetration of heat from said heated resilient pad into said hopper is prevented.

3. In a machine of the kind described, the combination of a support located at an applying station for supporting articles thereat in label receiving position, means located at a pick-up station spaced from said applying station for confining a stack of labels thereat, a heated pick-up device for removing successive terminal labels from said stack at said pick-up station and applying the same to successive articles at said applying station, said heated pick-up device subjecting the labels carried thereby to heat during the application thereof to said articles, and means cooperating with said label stack confining means for developing insulating air cushions therein whereby penetration of heat from said heated pick-up device into said label confining means is prevented.

4. In a machine of the kind described, the combination of a support for articles to be labeled, a hopper for confining a supply stack of adhesively coated labels, heated means for removing successive terminal labels from the stack in said hopper and applying the same to successive articles on said support, and means for introducing a plurality of air jets into said hopper, the latter confining the introduced air in the form of insulating air cushions whereby penetration of heat from said heated means into said hopper is prevented.

5. In a machine of the kind described, the combination of a support for articles to be labeled, a hopper for confining a supply stack of adhesively coated labels, heated means for removing successive terminal labels from the stack in said hopper and applying the same to successive articles on said support, and means co-operating with said hopper to develop confined insulating air cushions interiorly of said hopper whereby penetration of heat from said heated means into said hopper is prevented.

6. In a machine of the kind described, the combination of a support for articles to be labeled, means for confining a supply stack of labels provided with thermo-plastic coatings, means for removing successive terminal labels from the stack in said confining means and depositing said labels upon successive articles on said support, a pressure member for developing label applying pressure, and a heated resilient pad carried by said pressure member for pressing a previously deposited label into engagement with an article and for coincidentally heating said label to adhesively attach the same to said article, said pad conforming itself to the surface contour of said article.

7. In a machine of the kind described, the combination of a support for articles to be labeled, applying means for conveying adhesive coated labels into applying relation to the articles on said support, means for operating said applying means while in said applying relation in operative relation to said support whereby the adhesive coated labels carried by said applying means are applied to the articles on said support, and heating means combined with said applying means for heating the adhesive coatings of said labels through the latter coincidentally with the application of said labels to said articles.

8. In a machine of the kind described, the combination of a support for articles to be labeled, applying means for developing a label applying movement in operative relation to said support whereby adhesively coated labels are applied to articles thereon, and a heated resilient pad combined with said applying means adapted to conform to the surface contour of said articles and to heat said labels coincidentally with the application thereof to said articles.

9. In a machine of the kind described, the combination of a support for articles to be labeled, a reciprocable member for conveying adhesive coated labels over the operative path of said reciprocable member into applying relation to the articles on said support, means for actuating said member while in said applying relation in operative relation to said support to apply the adhesive coated labels carried by said reciprocable member to articles on said support, and means associated with said member for heating the adhesive coatings of said labels through the labels coincidentally with the application thereof.

10. In a machine of the kind described, the combination of a support for articles to be labeled, a reciprocable member, means for actuating said member in operative relation to said support to apply adhesively coated labels to articles on said support, and a resilient heated pad carried by said member adapted to conform to the surface contour of said articles and to heat said labels coincidentally with the application thereof.

11. In a machine of the kind described, the combination of a hopper for confining a supply stack of labels and enclosing said stack at least at the upper end thereof, and a suction head movable into substantially conterminous registry with the exit end of said hopper in spaced relation to and within suction range of the top of said stack whereby successive terminal labels are bodily lifted from said hopper into surface contact with said suction head and held thereon.

12. In a machine of the kind described, the combination of a hopper for confining a supply stack of adhesively coated labels and enclosing said stack at least at the upper end thereof to provide a walled space interiorly of said hopper, means co-operating with said hopper for developing confined air cushions in the walled space of said hopper between successive terminal and adjacent labels therein on which said terminal and adjacent labels are floated in separated relation to each other, means for preventing the air separated labels from being unintentionally forced out of said hopper by the action of the air therein, and a suction head movable into registry with said hopper in spaced relation to and within suction range of the top of said stack whereby successive floated terminal labels are intentionally withdrawn from said hopper into surface contact with said suction head and held thereon.

13. In a machine of the kind described, the combination of a hopper for confining a supply stack of adhesively coated labels and enclosing said stack at least at the upper end thereof to provide a walled space interiorly of said hopper, said labels being adapted to be successively removed from the top of said stack for application to successive articles, and means co-operating with said hopper for developing confined air cushions in the walled space of said hopper between successive terminal and adjacent labels therein on which said terminal and adjacent labels are floated in separated relation to each other

to prevent said labels from adhering to each other during the removal of successive labels from said stack.

14. In a machine of the kind described, the combination of a hopper for confining a supply stack of adhesively coated labels and enclosing said stack at least at the upper end thereof to provide a walled space interiorly of said hopper, said labels being adapted to be successively removed from the top of said stack for application to successive articles, means co-operating with said hopper for developing confined air cushions in the walled space of said hopper between successive terminal and adjacent labels therein on which said terminal and adjacent labels are floated in separated relation to each other to prevent said labels from adhering to each other during the removal of successive labels from said stack, and means for preventing the air separated labels from being unintentionally forced out of said hopper.

15. In a machine of the kind described, the combination of a hopper for confining a supply stack of labels provided with thermo-plastic coatings and enclosing said stack at least at the upper end thereof to provide a walled space interiorly of said hopper, said hopper being formed near its upper end with a plurality of inwardly directed air vents communicating with said walled interior space, and means for forcing air through said vents into said hopper, the latter confining the introduced air in the form of air cushions in the walled space of said hopper between successive terminal and adjacent labels therein on which said terminal and adjacent labels are floated in separated relation to each other to prevent said labels from adhering to each other during removal of successive labels from said stack.

16. In a machine of the kind described, the combination of a hopper for confining a supply stack of labels provided with thermo-plastic coatings and enclosing said stack at least at the upper end thereof to provide a walled space interiorly of said hopper, said hopper being formed near its upper end with a plurality of inwardly directed air vents communicating with said walled interior space, means for forcing air through said vents into said hopper, the latter confining the introduced air in the form of air cushions in the walled space of said hopper between successive terminal and adjacent labels therein on which said terminal and adjacent labels are floated in separated relation to each other to prevent said labels from adhering to each other during removal of successive labels from said stack, and means for preventing the

air separated labels from being unintentionally forced out of said hopper.

17. In a machine of the kind described, the combination of a hopper for confining a supply stack of labels provided with thermo-plastic coatings and enclosing said stack at least at the upper end thereof to provide a walled space interiorly of said hopper, said hopper being formed near its upper end with a plurality of inwardly directed air vents communicating with said walled interior space, and an air nozzle carried by said hopper in communication with said air vents and connected with a source of air under pressure whereby air is forced through said air vents into said hopper and across the same, said hopper confining the introduced air in the form of air separation cushions in the walled space of said hopper between successive terminal and adjacent labels therein on which said terminal and adjacent labels are floated in separated relation to each other to prevent said labels from adhering to each other during the removal of successive labels from said stack.

18. In a labeling machine for applying thermo-plastic coated labels, a suction head for carrying and applying said labels, and a heated resilient pad carried by said head for heating the thermo-plastic coatings through the labels provided with said coatings.

19. In a labeling machine for applying thermo-plastic coated labels, a suction head for carrying and applying said labels, and a heated resilient pad of porous heat conducting material carried by said head for heating the thermo-plastic coatings through the labels provided with said coatings.

20. In a labeling machine for applying thermo-plastic coated labels, a suction head for carrying and applying said labels, a heated resilient pad of metallic wool carried by said head for heating the thermo-plastic coatings through the labels provided with said coatings, and a plurality of flexible tubes embedded in said pad with their outer ends at the active surface thereof and their inner ends in communication with the interior of said head.

21. In a labeling machine for applying thermo-plastic coated labels, a suction head for carrying and applying said labels, and a heated resilient pad of heat resistant rubber carried by said head for heating the thermo-plastic coatings through the labels provided with said coatings.

22. In a labeling machine for applying thermo-plastic coated labels, means for depositing said labels on articles to be labeled, and a pressure member having a resilient heated pressure pad for developing pressure on said labels to complete the application thereof to said articles.

GEORGE W. VON HOFE.
